BUTTON

Ralph C. Bangs, Providence, R. I., assignor to
Core-Gram, Inc., New York, N. Y., a corpora-
tion of New York

Application December 7, 1936, Serial No. 114,563

2 Claims. (Cl. 24—113)

My invention relates to a new and improved button of the type which can be applied to garments, shoes, overshoes, and all articles of wearing apparel.

5 One of the objects of my invention is to provide a button having a removable face member which is made of metal or other suitable material, said face member preferably having an initial or a decorated design or the like formed thereon by 10 embossing or by any other suitable means.

Another object of my invention is to provide a device which shall be extremely simple and which can be manufactured and applied very cheaply.

Other objects of my invention will be set forth 15 in the following description and drawing which illustrate preferred embodiments thereof, it being understood that the above statement of the objects of my invention is intended generally to explain the same without limiting it in any manner.

20 Fig. 1 is a top plan view showing one embodiment of the invention, the representation of part of the face member having been broken away so as to illustrate the construction more clearly.

25 Fig. 2 is a sectional view on the line 2—2 of Fig. 1.

Fig. 3 is an inverted perspective view of the face member.

30 Fig. 4 is a top plan view showing another embodiment of the invention.

Fig. 5 is a sectional view on the line 5—5 of Fig. 4.

35 The embodiment of Figs. 1—3 has been illustrated in connection with a button which is used on an overshoe but it is to be understood that the invention is not limited to any particular use of the button.

40 Referring to Fig. 2, this shows the rubber material 1 of an overshoe, and the lining 2 thereof. The particular type of button which is illustrated in this embodiment has an inner tapered metal member 3, which is hollow. This member 3 is provided with a corrugated flange 4. The member 3 is made of metal or other suitable material 45 and the outer part thereof is rigid while the base thereof is springy.

The member 3 is reinforced by an outer shell 5, the base of which is imbedded in the material 1. The members 3 and 5 are applied with suitable 50 pressure so that they are clamped against the material of the overshoe. The face member 6 in this particular embodiment covers the button proper, which consists of the members 3 and 5. Said face member 6, in this embodiment, is em- 55 bossed so as to provide an initial 7. Said initial 7

may have a color which is different from the color of the exposed part of the face member 6.

Referring to Fig. 3, it can be seen that the cup-shaped face member 6 is provided with slits 7a, so as to provide resilient tongues 8. The slits 7a are formed at each side of each of the tongues 8 and said slits extend into the skirt 6a of the face member 6. Said face member 6 can therefore be stamped and shaped from a single piece of metal.

10 The tongues 8 have base portions 8a which are substantially perpendicular to the longitudinal axis of the face member 6.

When the face member 6 is pressed upon the button proper, the resilient tongues 8 can yield 15 outwardly, until they abut the material of the article to which the button proper is affixed. The base portions 8a of the tongues 8 therefore act as stops.

20 The face member 6 can be formed of thin sheet metal but it is substantially rigid due to the dome or cup-shape thereof. However, the slits 7a extend sufficiently into the skirt 6a of the face member 6, so as to permit the face member 6 to be forced into position over the tapered button 25 proper.

25 The resilient construction which is provided by the slits 7a causes the face member 6 to clamp the button proper, so that the face member 6 is held securely. However, the face member 6 can 30 be readily removed by bending the tongues 8 outwardly. The face member 6 can be applied again to the button member. This button member is a complete button, even if member 6 is removed.

35 In the embodiment shown in Figs. 4 and 5, the button member 9 is made of bone, mother of pearl, or any other suitable rigid material. It is a complete operative button, without the face member. The inner or rear face of said button 9 is provided with a recess 10a, and thread holes 40 11a can be provided, by means of which the button 9 can be sewed to the shirt or other garment. The recess 10a is then adjacent the material of the garment.

45 After the button 9 has thus been sewed to the garment, the face member 10 can be snapped into position over the button 9. Said face member 10 is made of metal or any other suitable material and it is provided with a plurality of outwardly 50 extending resilient arms 11 which are shaped to conform to the shape of the lateral surface of the button 9.

55 In this particular embodiment, I have shown four resilient arms 11, but any suitable number of such arms could be used. These arms are

preferably arranged in an opposed pair or in opposed pairs. The pitch diameter of the tips of the arms 11 is preferably less than the diameter of the lateral wall of the button 9. Hence, when 5 the face member 6 is pressed into position, the arms 11 are forced outwardly so that they resiliently engage the lateral wall of the button 9, thus firmly holding the face member 10 in position.

10 As shown in Fig. 5, the inner or base side of the button 9 is preferably provided with an undercut portion 9a which is of smaller diameter than the diameter of the outer or upper part of the outer lateral wall of the button 9. The arms 11 are provided with inwardly bent curved tips which snap underneath the shoulder which is formed by this undercut portion 9a, so that the face member 10 is securely held in position. However, after the face member 10 has been applied, it can be easily removed by using a suitable tool, without injuring said face member 10, so that said face member 10 can be reapplied to the button member 9.

In practice, the retailer will have a stock of 25 the face members 10, formed with different initials and when the retailer sells a shirt or other garment, the face members 10 will be applied so as to display the initial of the customer. If the wrong initial has been applied, this can be 30 easily removed.

Likewise if it is desired to launder or dry clean the garment, the face members can be readily removed and replaced.

I do not wish to be limited to any particular 35 form, style or shape of button, or to any particular use of the button. The button 9 could have any polygonal shape, instead of being circular in shape. Hence, whenever I refer to the transverse diameter of the button, I also refer 40 to the transverse dimension of a button which has a polygonal shape, such as a hexagon, an octagon, etc.

The outer face of the button preferably snugly abuts the corresponding portion of the inner face of the face member, save where the initial 45 7 or other decoration has been outwardly embossed.

In the embodiment illustrated in Figs. 4 and 5, the face member 10 has a cup-shape in effect, due to the configuration of the arms 11. This cup-shape is discontinuous because the

arms 11 are separated in this embodiment. However, and as previously stated, any desired number of arms 11 could be used, so that said arms 11 could be continuous, save where they are separated by slits, so as to provide the necessary 5 resilience.

In the embodiment shown in Figs. 1 and 2, the slits 7a extend outwardly so that the portions of the tongues 8 which abut the lateral surface of the button proper, are resilient and can spread outwardly when the face member is forced into position.

I have shown preferred embodiments of my invention, but it is clear that numerous changes and omissions can be made without departing 15 from its spirit.

I claim:

1. A composite button comprising a base member which has an end-face and an inwardly extending lateral skirt, and a face member also 20 having an end-face and an inwardly extending tapered lateral skirt, the inner end of the skirt of the face member being open and of smaller diameter than the end-face of the base member, said face member enclosing said base member 25 and being generally cup-shaped and having its skirt provided with pairs of slits which define intermediate resilient tongues, said tongues being sufficiently deep and resilient to permit the inner end of the skirt of the face member to be 30 forced over the end-face of the base member.

2. A composite button comprising a base member which has an end-face and a lateral skirt, and a face member also having an end-face and a lateral skirt, said face member enclosing said 35 base member and being generally cup-shaped and having its skirt provided with pairs of slits which define intermediate resilient tongues, said tongues having lateral extensions which extend outwardly relative to said skirt of the face member, the skirt of the face member being tapered inwardly from the end-face of said cup-shaped face member, said base member having a shape which is generally the same as that of the face member, said slits being of sufficient depth to cause said tongues to yield outwardly sufficiently so as to enable the skirt of the face member to be forced into position over the end-face of the face member, so as to enclose the skirt of the base member.

RALPH C. BANGS. 50
